G. A. TAYLOR

METHOD OF FINISHING PISTON RING GROOVES

Filed June 21, 1922

INVENTOR:
George A. Taylor
by Marjorie, Sam, Orveland & Dike, Atty.

UNITED STATES PATENT OFFICE.

GEORGE A. TAYLOR, OF BOSTON, MASSACHUSETTS.

METHOD OF FINISHING PISTON-RING GROOVES.

Application filed June 21, 1922. Serial No. 570,020.

To all whom it may concern:

Be it known that I, GEORGE A. TAYLOR, a citizen of the United States, residing at Boston, county of Suffolk, State of Massachusetts, have invented a certain new and useful Improvement in Methods of Finishing Piston-Ring Grooves, of which the following is a specification, reference being had therein to the accompanying drawings.

10 My invention relates to the manufacture of pistons for internal combustion engines and like articles which are provided with annular slots in which the piston rings are placed. It is important that the parallel 15 walls of these slots shall be true, of the correct distance apart, and as highly finished as possible, so that a gas tight seat shall be made between the proximate faces of the ring and groove. My present invention, 20 therefore, has for its object a novel method of enlarging, truing and finishing ring slots in pistons and like articles. The method consists primarily in forcing or rolling through the slots a sharp-edged disk the 25 width of which is slightly greater than the original width of the slot so that the edges of the disk shear or scrape off from the side walls of the slots a minute layer of metal, leaving the surface of the metal scraped or 30 highly polished and the groove of uniform diameter throughout. In practice I find that all the grooves of a piston can be finished at the same time by the use of a plurality of axially movable disks mounted on 35 an arbor.

In practicing my novel method, I employ disks with sharp edges having a shearing action so that they scrape or otherwise remove from the parallel surfaces of the 40 groove a minute layer of metal. I find in actual practice that this results in the production of a highly finished surface and renders the groove true and accurate in width throughout its length, thereby producing 45 a surface or surfaces against which the corresponding surface or surfaces of the piston ring will seat and make a gas-tight joint.

The invention will be fully understood 50 from the following description when taken in connection with the accompanying drawings, and the novel features thereof will be pointed out and clearly defined in the claim at the close of this specification.

55 In the drawings, Fig. 1 is a view of a ma-

chine for practising the novel method embodying my invention.

Fig. 2 is a section taken on line 2—2 of Figure 1.

Fig. 3 is a detail view showing the construction of one of the roller disks used in the finishing operation.

Fig. 4 is a view on an enlarged scale of the grooved portion of the piston showing the effect on the piston of the finishing method described herein.

Referring now to the drawings, at 11 is shown a piston having three grooves, *a*, *b* and *c*. These grooves are formed by ordinary methods and machined. Thereafter, 70 the piston is supported on an arbor 12 which can be rotated by a pulley 13. In a suitable position adjacent the piston 11 are a plurality of disks 14, 15 and 16 which, in the machine shown in the drawings, are 75 themselves supported on an arbor 17 mounted in bearings 25 on suitable brackets 18 which are carried by a slide 20. The said disks are separated by spacers 19, 19, and are capable of slight axial movement lengthwise of the arbor. They are also loose on the arbor. Each of the disks, as shown in Figure 3, has flat end faces *d* and *e*, and a smooth cylindrical peripheral surface *f* making sharp peripheral edges *g* and *h*. The 80 thickness of the disk is slightly greater than the width of the groove in which it is to be used. In practice I find that it is well to make the disk .004 or .005 of an inch thicker than the width of the groove so that the 85 shaving or scraping which will be removed will be from .002 to .002½ of an inch in thickness.

To finish the walls of the grooves *a*, *b*, and *c* in the piston, disks are moved up to the 90 piston on the slide 20 on which the stationary arbor 17 is mounted. The piston is then caused to revolve slowly and the slide 20 fed toward the axis of the piston so that the disks gradually enter the grooves and 95 as the piston revolves the disks are rotated, removing progressively a minute portion *i* of the surface, shown in Figure 4, and leaving the walls in a highly polished condition and of uniform width. The shavings or 100 scrapings are forced into the bottom of the groove and are so minute that they do not interfere with the operation of the disks.

While my invention in its broadest form 105 contemplates the use of a single disk to fin-

ish the flat surface of a piston ring groove, in practice I employ as many disks as there are grooves, performing the operation on all of the grooves simultaneously in the 5 manner shown. This is perfectly practicable, since the disks, if mounted to be slightly movable axially of the arbor on which they are mounted, adjust themselves to any variations in the relative position of 10 the grooves.

The method embodying my invention not only produces a better piston than has heretofore been produced, but does so without subjecting it to any undue strains, as is the 15 case where an attempt is made to compress the metal of the walls of the grooves.

In the foregoing description of the disk

employed, I have used the expression a "sharp edge" to designate the construction of the tool employed. By the phrase "sharp edge," I intend to connote any edge which has the effect of cutting, i. e. removing metal from the wall in distinction to one which by reason of its shape or character is incapable of doing so. 20 25

What I claim is:

The method of enlarging, truing and finishing the ring slot in a piston or the like article, which consists in passing through the slot a disk-shaped roller having a sharp edge, 30 the width of the roller being slightly greater than the original width of the slots.

In testimony whereof I affix my signature.
GEORGE A. TAYLOR.
